HEATING ELEMENT FOR CANNED FOODS
 Russell Bliss Akin, Wilmington, Del., assignor to E. I. du Pont de Nemours and Company, Wilmington, Del., a corporation of Delaware

Filed Mar. 16, 1961, Ser. No. 96,315
 5 Claims. (Cl. 126—252)

This invention relates to a novel means for heating canned foods, and, more particularly, it relates to a shaped polymeric material capable of heating canned foods.

Campers, soldiers, and others who live outdoors have always had the problem of providing themselves with hot food without also burdening themselves with cooking equipment. Military forces have heated canned food by the use of tablets of trioxane as fuel. This fuel has many advantages such as low luminosity and slow rate of burning, but it has the same disadvantage as any natural fuel in that the canned food must be heated through the bottom of the can, thus frequently causing scorching of the food at the bottom of the can.

It is an object of this invention to provide a novel fuel element for heating canned food. It is another object of this invention to provide a slow-burning fuel element which can be used to heat the contents of a can of food without the danger of scorching the food. It is another object of this invention to provide a novel method of attaching fuel to a can. Still other objects will appear from the detailed explanation of the invention which follows:

The foregoing objects are accomplished by providing a shaped structure of polyoxymethylene, the structure being such that it fits closely around the lower portion of the outside surface of the can. This structure may be in the form of a springy helical coil of an elongated strand, or it might be a cup-shaped cover to be placed around the can, or it might be a springlike cylindrical sheet to be snapped into place around the can. In the preferred embodiment of this invention the structure comprises a medium to high molecular weight polyoxymethylene with or without additives to provide or enhance certain features. A flame-propagating means may be applied to the lower extremities of said structure so as to provide a quick and even ignition of the structure on all sides of the can.

A more complete understanding of this invention may be had by an inspection of the attached drawings. FIGURE 1 shows a can 1 with the fuel element in the form of a helical coil 2 wrapped around the lower portion of the outside of the can. The cross-section of the strand forming coil 2 may be solid or hollow and may be round, rectangular, triangular, or any other convenient shape. In FIGURE 2 the can 1 has a fuel element in the form of a springlike sheet 3 which can be spread open far enough to be slipped over the can and then released so that by spring action the sheet will close tightly around the can. In FIGURE 3 the can 1 is placed into a fuel element 4 in the shape of a cup which fits closely to the outside contour of the can. If desirable, the upper edge of the cup 4 may be formed into a series of fingers or scallops 5 which are directed inwardly so as to apply a slight pressure against the can and thereby provide the frictional engagement to hold cup 4 in place. It will be understood that in any of these shapes, some of the combustible element may extend under the bottom of the can. In FIGURE 4 the can 1 has a fuel element 7 which is in the form of a helical coil of a tape shown in this embodiment to have a generally rectangular cross section.

Although there are several plastic materials which can be burned and which can be formed into the shapes of these fuel elements, polyoxymethylene is especially de-

2

sirable for this purpose. It burns slowly, with an imperceptible, blue flame, and without producing any ash, smoke, or soot. Polyoxymethylene is physically strong, unaffected by moisture, and can be fabricated into durable shapes which are flexible, tough, and springlike.

The burning characteristics of polyoxymethylene are such that if the coil 2, the sheet 3, or the cup 4 of the attached drawings were ignited at one location around the circumference of the can 1, the flame from the burning polyoxymethylene would not rapidly distribute itself completely around the circumference. As a consequence, uneven heating of the contents of the can would result. Therefore, it is preferable that some flame-propagating means be provided around the lower extremities of the fuel element. This means is shown at 6 on each of FIGURES 1, 2, 3, and 4. Several alternative means may be employed. The polyoxymethylene may be roughened or cut into small slivers or shavings to make it easier to ignite in the same fashion as kindling wood is prepared. A coating, which is much easier to ignite than polyoxymethylene, for example, nitrocellulose lacquer, may be applied to the lower portion of the fuel element. Still another alternative which has been found to be highly desirable is to apply a coating which consists of 3 parts by weight of nitrocellulose lacquer and 1 part by weight of feathery, fluffy particles of polyoxymethylene. A typical nitrocellulose lacquer might have the following composition:

	Grams
30 Dry nitrocellulose	18
Ethanol	11
N-butanol	10.7
Toluene	9.8
Xylene	17.3
35 Methyl ethyl ketone	16.6
Butyl acetate	16.6
Total	100.0

40 Other flame-propagating means can be employed with equal effectiveness. The only requirement is that the flame be spread completely and rapidly around the can so that it may then cause the polyoxymethylene on all sides of the can to burn at about the same time. If a self-igniting fuel element is desired, the head of a match may be affixed to the flame-propagating means so that the fuel element can be put to use by merely striking that match.

45 The amount of polyoxymethylene in the fuel element will depend upon the thermal characteristics of the material to be heated as well as the characteristics of the polyoxymethylene itself. In use as a fuel element it can be considered that about 7000 B.t.u. of heat is theoretically available per pound of polyoxymethylene burned. In actual tests it has been found that about 10-30% of the available heat is actually transferred to the contents of the can. For most types of canned foods a fuel element containing from about 25-50 grams of polyoxymethylene per pound of food or per pint of liquid may be employed to heat the contents of the can from a temperature of about 35-50° F. up to about 150-200° F.

50 The fuel element should fit the sides of the can as closely as possible so that there is no insulating layer of air between the fuel element and the can. This will help to insure the maximum efficiency for utilizing heat.

55 There are several reasons why polyoxymethylene is particularly desirable for use in the fuel element of this invention. Polyoxymethylene melts at about 340°-350° F. For the purposes of heating food without scorching it is a desirable temperature to apply to the outside of the can. The flame of the burning polyoxymethylene is, of course, at a much higher temperature, but it is in-

sulated from the can by a layer of molten polyoxymethylene.

The polyoxymethylene must be fabricable into the shapes desired for these fuel elements. Generally, this means that the polyoxymethylene must have a number average molecular weight of at least 10,000. The higher the molecular weight, the better will be the strength properties of the polyoxymethylene, such as the spring action to clamp or to coil tightly around the can. These strength properties also prevent the polyoxymethylene from splitting or fracturing in some fashion that would permit the fuel element to fall away from the can. This has been a disadvantage of the previously used low molecular weight polymers of oxymethylene, such as trioxane.

The following examples illustrate the use of the fuel element of this invention.

Example 1

High molecular weight plastic polyoxymethylene was extruded in the form of a tubing $\frac{3}{16}$ inch in diameter with a wall thickness of 26 mils. The tubing was wrapped in the form of a helical coil over a mandrel $2\frac{1}{4}$ inches in diameter and annealed in an oil bath at 320° F. for 20 minutes. After removal of the coil from the mandrel it relaxed to form a coil with an inside diameter of about $2\frac{1}{2}$ inches. The coil was then cut to an axial length of about $2\frac{1}{2}$ inches. Two turns at one end of the coil were coated with a nitrocellulose lacquer containing about 25% by weight of featherly particles of polyoxymethylene, followed by two coats of unmodified nitrocellulose lacquer. The lacquer was dried in an air oven at 70° F. for one hour.

A coil prepared as described above, containing about 33 grams of polyoxymethylene, was wrapped around a can of beef stew (contents of the can weighing 190 grams). The fuel element was ignited with the stew being at a temperature of 35° F. In 7-8 minutes in a moderate breeze the temperature of the stew was raised to 150° F. and there was no evidence of scorching of the stew.

Example 2

Several experiments were run to determine some of the characteristics of this fuel element when used to heat a given amount of water in a can. The same type of fuel element was employed as that described in Example 1. In each instance 190 grams of water at 35° F. was heated with a fuel element with the following results:

Test No.	Fuel Weight, Grams	Time to Complete Combustion, Min.	Maximum Temperature Reached, F.	
1	13.0	5	155	55
2	22.0	7	180	
3	33.5	9	197	

It is not intended that this invention be limited to fuel elements composed entirely of polyoxymethylene. Many combustible materials are granular or are frangible, or are otherwise not suitable for preparation into structural shapes. These materials might, however, be mixed with a

resinous polyoxymethylene and the resulting mixture could be fabricated into structural shapes. Thus, the heating element of this invention may comprise polyoxymethylene mixed with any of a wide variety of materials which may aid in the combustion of the element; for example, combustible carbonaceous materials, oxidizing agents, and intumescing agents. It may be desirable in some instances to provide a high surface area, for example, by employing a cellular, or foamed, polyoxymethylene; or alternatively by employing a ribbed or porous form of polyoxymethylene.

The foregoing description illustrates several embodiments of this invention, but it is not intended that the invention be limited in any fashion other than as described in the appended claims.

There are several related materials of construction which are equivalent in this invention because they consist primarily of recurring oxymethylene ($-\text{CH}_2\text{O}-$) units. These materials are all labelled "polyoxymethylene" herein. The polyoxymethylene intended to be employed in this invention may be a homopolymer of formaldehyde or of trioxane or it may be a copolymer, blend, or mixture of these polymeric substances with other materials. It is important only that the polyoxymethylene employed have (1) sufficient strength to be fabricated into stable shapes and to have the spring-like resiliency needed to provide frictional engagement between the heating element and the can, and (2) a chemical structure such that the combustion characteristics are substantially the same as those of the homopolymer of formaldehyde.

I claim:

1. The combination of a can of food and a fuel element adapted for use in heating said can, said fuel element being composed of a high molecular weight, thermoplastic, fabricable polyoxymethylene and being in the form of a hollow cylindrical article, the wall of which has the natural springlike resiliency of said polyoxymethylene and which is of such a size as to fit snugly around said can which is to be heated, the exact shape and form of said wall being such as to permit said article to be manually radially expanded sufficiently to be placed around said can, and, upon release, to radially contract and to grip said can with sufficient pressure to remain in position around said can without other means of attachment.
2. The combination of claim 1 in which said hollow cylindrical article is a helical coil of a tube.
3. The combination of claim 1 in which the said hollow cylindrical article is a helical coil of a tape.
4. The combination of claim 1 in which the said hollow cylindrical article is a cup-shaped cover fitting over the lower portion of said can.
5. The combination of claim 1 in which the said hollow cylindrical article is a solid sheet substantially encircling the sides of said can.
